UNITED STATES PATENT OFFICE.

WILLIAM GRETHER, OF DAYTON, OHIO.

PORTABLE ELECTRIC LANTERN.

1,286,590.

Specification of Letters Patent.

Patented Dec. 3, 1918.

Application filed June 27, 1918. Serial No. 242,241.

To all whom it may concern:

Be it known that I, WILLIAM GRETHER, a citizen of the United States, residing at Dayton, in the county of Montgomery and 5 State of Ohio, have invented certain new and useful Improvements in Portable Electric Lanterns, of which the following is a specification.

This invention relates to new and useful 10 improvements in portable electric lanterns.

The principal object of the invention is to provide a portable electric lantern whose size and weight are reduced to the minimum 15 without sacrificing any of its utility and attractive features.

Another object of the invention is to provide a lantern having two compartments which are completely separated from each 20 other, the rear compartment being adapted to receive a storage battery and the front one forming an air-tight and gas-proof compartment for the reflector.

Another object of the invention is to provide 25 a portable electric lantern having the focusing device in front, whereby the lantern may be carried by one hand and the focusing device operated by the other. Focusing devices placed in the central and rear 30 portions of the lantern, are difficult to operate without setting the lantern down.

Another object of the invention is to provide 35 for the lantern, a handle which equally distributes its weight and by which it may be carried in a natural position. The handle does not have to be removed to charge the storage battery, and the lantern may be carried by said handle about the charging station with the cover removed. By swinging 40 the handle about its hinge, the storage battery may be removed.

Another object of the invention is to provide 45 a switch at the top of the lantern, that may be operated by the same hand that carries it.

Another object of the invention is to provide 50 means for effecting an instantaneous electric connection between the battery and the lamp when the cover is placed upon the case, and as quickly breaking the connection when the cover is removed.

Another object of the invention is to provide 55 means in the cover for shedding water from the interior and permitting the escape of gas.

Another object of the invention is to pro-

vide means at the front of the lantern to prevent its tipping; and if dropped, to protect its weaker parts.

Other important and incidental objects 60 will be brought out in the following specification and particularly pointed out in the subjoined claims.

The preferred form of embodiment of my invention is illustrated in the accompanying drawings, of which Figure 1 is a vertical sectional view of my improved portable electric lantern. Fig. 2 is an end view of the rack and pinion device for obtaining the proper focus. Fig. 3 is a front elevation of 70 the lantern. And Fig. 4 is a top plan view thereof.

Throughout the specification and drawings, similar reference characters denote 75 corresponding parts.

In a detailed description of the preferred form of embodiment of my invention, the numeral 1 designates the lantern casing which is preferably constructed of aluminum. This casing is divided by a vertical wall 2, into two compartments 3 and 4, the rear compartment 4 being preferably rectangular in transverse section. The front compartment comprises a neck portion 5 which extends outwardly from the front top portion of the case at right angles thereto, terminating in an outwardly flaring reflector support 6, preferably of bell shape. The compartment 4 terminates at its forward middle portion in a knee 7, to prevent 80 it from tipping forward when placed upon a supporting surface; and to assist in protecting the front portion of the lantern from injury should the latter be dropped.

The rear compartment 4 of the lantern 95 casing 1 contains a storage battery 8, preferably of the two-cell, four-volt type. The compartment 4 is adapted to receive a cover 9 having ledge bosses 10 through which wing head screws 11 are passed into corresponding bosses 12 on said compartment top, said wing head screws enabling the cover to be applied or removed from the case without the use of a screw driver or other means.

When the cover 9 is applied to the top of the compartment 4, an instantaneous electrical connection is made between the battery terminals 13 and a wire 14 leading to a lamp socket 15, and a wire 16 leading to 110 a switch 17, by the following means. (See Figs. 1 and 4.) Secured by means of screws

- 18 to the top of the cover 9, above the battery terminals 13, is an insulating piece 19, preferably made of Bakelite and rectangular in cross section. Projecting downwardly 5 from the piece 19, for contact with the battery terminals 13 when the cover 9 is applied to the top of the lantern case, are two spring plunger contacts 20 preferably made of phosphor bronze.
- 10 A wire 21 leads from each plunger contact 20 to a similar spring plunger contact 22 in a Bakelite insulating piece 23 similar to the piece 19, the latter being secured in a recessed portion 24 of the cover 9 by means 15 of screws 25. A similar insulating piece 26 is secured in a recessed portion of the compartment 4, below the insulating piece 23, and contains two spring plunger contacts 27 adapted to be engaged by the contacts 22 20 when the cover 9 is applied, for the purpose of conducting current from the battery 8 to the said spring contacts 27. From one spring contact 27 in the latter, the wire 14 leads to the lamp socket 15, while the other 25 contact 27 thereof receives the wire 16 from the switch 17, said lamp socket and switch being directly connected by a wire 28. (See Fig.) It will thus be seen, that by virtue 30 of the spring-contact insulating pieces 19, 23 and 26, an electric circuit will be instantaneously closed through the battery, lamp and switch, the moment the cover 9 is applied to the top of the casing 1, and that this circuit will be broken the instant said 35 cover is removed. To apply or remove said cover it is therefore only necessary to properly position the latter on the case and insert or remove the wing head screws 11, and no other adjustments need be made to close 40 or open the circuit between the battery and the lamp.
- 45 The switch 17, which is preferably of the Cutler Hammer type, is operated by a push rod 17^a which extends above the neck portion 5 of the lantern case, whereby the switch may be conveniently operated by the same hand that carries the lantern.
- 50 In order to make the compartment 4 weatherproof, a gasket 29, preferably constructed of sheet rubber, is placed between the cover 9 and the top of said compartment. The body of the storage battery 8, extending 55 to the top of the casing, is prevented by said gasket from rattling.
- 55 On the exterior top middle portion of the rear wall of the lantern casing 1, is a lug 30 to which is hinged, by wing-head screws 31, the bifurcated rear end of a curved handle 32. The front end of the latter is bifurcated for removable connection, by means 60 of wing-head screws 33, to a lug 34 on the middle top portion of the reflector support 6. The handle 32 extends from the extreme front, to the extreme rear portion of 65 the lantern to enable the latter to be carried

by one hand in its natural position and at the same time distribute equally thereon the weight of the lantern. To remove or insert the storage battery 8, it is only necessary to remove the wing-head screws 33 and 70 turn the handle back about its rear hinge, or said handle may be hinged in front without departing from the spirit of the invention. (See Figs. 1 and 3).

Provided in the rear wall of the cover 9 75 is a vent hole 35 disposed at an approximate angle of 45° to shed water away from the interior of the device and to provide an outlet for any gas that may accumulate in the compartment 4. (See Fig. 1).

Coming now to a description of the elements within the compartment 3, the numeral 36 designates a preferably silver-plated parabolic reflector terminating rearwardly in a hollow neck portion 37 preferably spun thereon. This neck portion 37 provides a tubular guide through which the lamp socket 15 is longitudinally movable. Secured within the socket 15 is a preferably tipless bulb, 4-volt lamp 39 in front 90 of which a clear glass lens 40 is maintained by a circular lens holder 41. As described in my former application Serial No. 179,384, this holder has external peripheral bosses 42 through which screws 43 are passed into 95 corresponding bosses 44 formed on the rim of the reflector support 6, to firmly, yet removably, secure the lens holder 41 to the latter. An annular copper-asbestos gasket 45 is interposed between the lens holder 41 100 and the reflector support 6 to make a waterproof and air-tight compartment for the reflector. (See Fig. 1).

For the purpose of moving the lamp 39 forward to secure a diffused or flood light, 10 or to the rear for the purpose of obtaining a spot light, of varying intensity, the following described focusing device is provided in the front compartment 3. Referring again to Fig. 1, there is secured to the 11 rear portion of the socket 15, an L-shaped piece 46 whose foot portion is screwed to a short rack 47 provided with a downwardly extending guide flange 48 on each side thereof. (See Fig. 2). The rack 47 is adapted 11 to be engaged from below, between the flanges 48 48, by a small pinion 49 fixedly secured to a screw rod 50 which loosely extends through a bore in a lug 51 on the lower neck portion of the lantern casing, 12 which may be conveniently turned by one hand, while the lantern is held in the other. It is therefore unnecessary to set the lantern down to operate the focusing device, as in cases where the focusing devices are provided in the rear portion of the lantern. 13

When the screw rod 50 is turned, it will move the rack 47 forwardly or rearwardly, depending upon the direction of its rotation, to obtain the desired focus for the lamp. 14

Secured to the partition 2 by a screw 51^a, is a set spring 52 on whose free end there is a small knob 53 adapted to resiliently engage the teeth of the pinion 49 for the purpose of firmly holding the lamp 39 at the selected focus.

To prevent the ignition of leaking gas or explosives by sparks that might be produced in the reflector should the lens 40 in 10 any way become broken, the following safety device is provided to break the lamp circuit as described in my before mentioned application Serial No. 179,334. Secured by screws 54 to the interior rim portion of the 15 lens holder 41, is a wire 55 that extends from one of said screws to the other in approximate alignment with the diameter of the lens 40. The wire 55 is preferably successively arched as shown in Fig. 1. To the middle 20 part of the narrow central arched portion of said wire the pointed end of a conical-shaped, spiral spring 56 is secured, the rear portion of which engages the front part 25 of the lamp bulb 39. The wire 55 serves to firmly and fixedly hold the spring 56 at the proper point in front of the lamp bulb 39.

Bearing against the rear portion of the lamp socket 15 is a similar conical spring 57, the rear end of which is secured by a 30 screw 58 to the partition 2. Each of said springs serves as a resilient buffer for the lamp during its forward or rearward movement, said forward movement of the lamp being limited by the engagement of the 35 front part of the rack 47 with the reflector 36, and the rearward movement of said lamp being limited by the engagement of the rear end of the rack 47 with the partition 2. Should the lens 40 be broken in any way, the 40 spring 56 will have a sufficient unrestrained forward movement to permit the lamp circuit to be broken as described in my aforesaid application, thereby preventing the ignition of any gases that may find their way 45 into the reflector.

Extending from side to side on the rear wall of the lantern casing 1, is a boss 58 to which is preferably screwed a bracket plate 59 whose humped central portion is adapted to receive a tongued support of any suitable design (not shown).

I do not wish to be limited to the details of construction and arrangement herein shown and described, and any changes or 50 modifications may be made therein within the scope of the subjoined claims.

Having described my invention, I claim:

1. A portable electric lantern comprising a casing having two compartments, a battery in one compartment and an electric lamp in the other, a removable cover for the battery compartment, a contact piece within said cover adapted to engage the terminals of said battery when the cover is applied to 55 said case, a contact piece secured within the

upper portion of said casing and in electric connection with said lamp, and a contact piece at one side of said cover, adapted to engage the last mentioned contact piece when the first contact piece engages the terminals of said battery, whereby, when the cover is applied, an instantaneous electric connection is established between said battery and lamp, and again broken when said cover is removed. 70

2. A portable electric lantern comprising a casing having two compartments, a battery in one compartment and an electric lamp in the other, electric means connecting said battery and lamp, a cover for the battery compartment through which said means extend, the lamp compartment comprising a narrow neck portion having an outwardly flaring mouth, a switch in said neck portion in circuit with said lamp and battery, and a push rod extending upwardly through said neck portion for operating said switch. 80

3. A portable electric lantern comprising a casing divided into two compartments, a lamp in one compartment and a battery in the other compartment, said lamp compartment comprising a narrow neck portion extending outwardly from the top of the battery compartment and terminating in an outwardly flaring mouth, and a handle 90 hingedly secured to the top rear portion of the battery compartment and extending forwardly for removable connection to the top edge of said outwardly flaring mouth portion of the lamp compartment. 95

4. A portable electric lantern comprising a casing divided into a front and rear compartment, a lamp in the front compartment and a battery in the rear compartment, means for connecting said lamp and battery, a focusing device for said lamp in the front compartment, and means for operating said focusing device, extending through one side of said front compartment, whereby the focusing device may be operated by one 100 hand and the lantern carried by the other. 110

5. A portable electric lantern comprising a casing divided into two compartments, a lamp in the front compartment and a battery in the rear compartment, electric means for connecting said battery and lamp, a reflector behind said lamp in the front compartment, a socket for the lamp longitudinally movable through said reflector, a rack secured to said socket, a pinion for imparting a longitudinal movement to said rack, and a screw rod for turning said pinion, extending through a side of the front compartment. 115

6. A portable electric lantern comprising a casing, a reflector support projecting from the front portion of said casing, a longitudinally movable lamp in said reflector casing, a lens in front of said lamp, an interior wire extending from one side of said lens to the 120 125 130

other, and a spring attached to the middle portion of said wire, for engagement, at its rear end, with said lamp for the purpose described.

7. A portable electric lantern comprising a casing, a reflector support projecting from the upper front portion of said casing, and a projecting knee on the lower front portion

of said casing to prevent said lantern from tipping forwardly when placed on a supporting surface. 10

In testimony whereof I have hereunto set my hand this 25th day of June, 1918.

WILLIAM GRETER.

Witness:

MAY BISHOP.
